CIGARETTE PACKAGE RECEPTACLE

Joseph Halpern, New York, N. Y.

Application October 8, 1952, Serial No. 21,757

Term of patent 14 years

(Cl. D85—2)

To all whom it may concern:

Be it known that I, Joseph Halpern, a citizen of the United States of America, residing in New York city, county of Bronx, and State of New York, have invented a new, original, and ornamental Design for a Cigarette Package Receptacle, of which the following is a specification, reference being had to the accompanying drawing, forming part thereof, wherein,

I claim:

The ornamental design for a cigarette package receptacle, substantially as shown.

JOSEPH HALPERN.
